Application November 17, 1955, Serial No. 547,482

11 Claims. (Cl. 197—16)

This invention relates to typewriters and more particularly to an improved single element typewriter having an improved selecting and printing mechanism.

By definition, a single element typewriter is one having a single element printing head wherein all the characters of a type font are positioned on the surface of one printing device, which device may be positioned for printing engagement with a paper carrier with a selected character of the type font in printing position.

It is well known in the typewriting art that much of the noise of conventional typewriters is a result of the print action of a low mass high velocity type bar. Printing noise may be reduced materially through the use of a high mass low velocity printing head, and it is a first object of this invention to provide such an improved quiet printing mechanism.

In earlier single element typewriters, the mass behind each character at the instant of printing was not uniform, with the natural result that print density of the characters varied, and accordingly it is a further object of this invention to provide an improved single element typewriter wherein the mass behind each print blow is substantially uniform.

It is a further object of this invention to provide an improved typewriter wherein the paper holder is stationary while the printing element is moved across the page whereby the machine requires less operating room.

It is a further object of this invention to provide a stationary paper holder typewriter whereby the printing mechanism may be enclosed to reduce the noise.

It is a further object of this invention to provide an improved typewriter wherein the type font is readily interchangeable.

It is a further object of this invention to provide an improved single element typewriter wherein the rate of print strokes is cyclically controlled to provide a predetermined minimum time between print strokes.

It is a still further object of this invention to provide a single element typewriter having an improved case shift mechanism.

It is a further object of this invention to provide a single element typewriter having an improved selecting mechanism for determining the character that is to be printed.

It is a still further object of this invention to provide a single element typewriter having an improved selecting mechanism which facilitates adapting the machine for remote control.

It is a still further object of this invention to provide a typewriter having a character selecting mechanism wherein a uniform key lever force triggers a power operated selection.

Other objects of the invention will be pointed out in the following description and claims and illustrated in the accompanying drawings, which disclose, by way of example, the principle of the invention and the best mode, which has been contemplated, of applying that principle.

In the drawings:

Fig. 14 is a timing diagram.

Briefly, this invention relates to an improved single 50 element typewriter acting in combination with mechanisms for cyclically selecting and printing a predetermined character. In a preferred embodiment, the printing element is character spaced across a page and at each printing position, a cycle of operation is instituted in response to manipulation of a key lever wherein one character is first selected, and then printed.

Referring to the drawings, a typewriter 2 is shown comprising a body 4, a paper feed unit 6 and a movable single element type head 8 which traverses the paper feed unit 6 and prints successively in columns in normal printing fashion. The type head 8 is supported on a carriage 10 which is movable along guide rails 12, 14 across the paper feed unit. In this respect, this typewriter is unconventional in that the paper feed unit remains stationary while the printing element moves across the page.

60 The typewriter is also provided with the usual key levers 16 having their own key buttons 18, respectively. The key levers 16 (Fig. 2) are shown pivotally supported about a fulcrum rod 20 which extends transversely of the machine in a conventional manner. When a key lever is rocked counterclockwise within the limits defined by a conventional guide comb 24, it acts on an interposer

22 (one for each key lever, respectively). The interposers are pivotally supported about fulcrum rod 26 (which extends transversely of the machine) in such a manner that each interposer can both be rocked clockwise about the fulcrum rod 26 and slid transversely within the limits defined by the slotted opening 28.

Each key lever 16 is provided with a finger 30 which acts on a bent over ear 32 extending integrally from the corresponding interposer 22. Actually, the finger 30 pushes on the bent over ear 32 to rock the interposer clockwise about the fulcrum wire 26, and in doing so, a bail 34, which extends transversely of the machine, is moved downward to a tripping position as well as hereinafter explained.

The bail 34 is used to trigger a clutch which will be later described to cause a one-third revolution of a filter shaft 36. It will be noted that when the interposer 22 has been rocked clockwise into an active position (dotted line position of Fig. 2), an actuating shoulder 38 is positioned for engagement by one of the lobes 40 of the filter shaft 36, which lobe will drive the interposer 22 to the left as viewed in Fig. 2 within the limit of the elongated slot 28. In this movement of the interposer shaft to the left, it will be noted that a plurality of selecting fingers 42 which are an integral part of the interposer 22 will act to rock predetermined selecting bails 44 about their pivots 46. Actually, the selecting fingers 42 are arranged in some combination of seven so that any number of selecting bails 44 (up to seven) may be rocked about their pivots respectively. That is, there is one individual combination of the seven fingers for each key lever 16, respectively.

Each selecting bail 44 is connected to a selecting link 48 (Fig. 3), which is movable to the right as viewed in Fig. 2, in response to the rocking of its assigned selecting bail. The selecting links 48, in turn, are employed to control the operation of clutch mechanisms which will be hereinafter described.

Operation of the filter shaft

With reference to Fig. 3, a filter belt 50 is illustrated as being driven under control of a motor, not shown, to drive a filter pulley 52 in a counterclockwise direction as shown by the arrow in Fig. 3. It has been mentioned that the bail 34 is depressed each time a key lever is rocked. Actually, as shown in Fig. 3, the bail 34 is pivotally supported about an axis 53 of a crank member 54 which, in turn, is supported in the side frame. The rocking of the bail 34 about its axis 53 causes a filter pawl 56 (attached to crank member 54) to be lifted out of engagement with a lobe on a primary filter cam 58. (See Fig. 3A.) Actually, as shown in Fig. 3A, the pulley 52 is rotatable freely about the filter shaft 36. But pulley 52 is connected via a filter or spring clutch 60 to the filter shaft 36. In detail, the filter clutch 60 comprises a primary member 58 and a secondary member 64, with the secondary member being pinned or otherwise secured by a set screw to the filter shaft 36 and with the primary and secondary members being interconnected via a coil spring 66. When in the position shown in Fig. 3, the coil spring will be unwound to a large diameter thereby permitting the hub of pulley 52 to rotate freely on the filter shaft 36; but when the spring clutch is tightened, it will grip the hub of pulley 52 and thereby drive the filter shaft 36. In the illustration shown in Fig. 3, the filter pawl 56 is in engagement with a lobe on the primary 58 of the filter clutch 60 and when the pawl 56 is lifted out of engagement with a lobe on the primary, the spring 66 tightens to cause rotation of shaft 36. The complementary pawl 68 serves merely to prevent a back lash of the secondary member 64 and thereby insures the release of the spring 66 when the pawls are in the position shown in Fig. 3. After the filter pawl 56 is raised out of engagement with the lobe on the primary 58, filter shaft 36 will rotate until the pawl 56 engages the

next succeeding lobe on the primary 58. More specifically, with reference again to Fig. 2, it was mentioned that the lobe 40 on the filter shaft 36 pushes on the actuating shoulder 38 to drive the interposer 22 to the left. It will be noted that the interposer 22 is spring biased by the spring 70 upward and to the right. Accordingly, it can be appreciated that when the interposer 22 is driven to the left, and as soon as it is removed from contact with the key lever tripping finger 30, the spring 70 will take over tending to pull the interposer counterclockwise about the fulcrum 26, which action will disengage the interposer from the filter shaft 36 and thus release the bail 34 which in turn will restore the trip pawl 56 to the position shown in Fig. 3. In order to insure this disengagement, a stop 71 is positioned transversely of all the interposers to engage a camming ear 73 which forces the interposer upward. Actually, the arrangement of parts is such that after the filter shaft 36 has made one-ninth of a revolution, the interposer 22 will be disengaged from the tripping finger 30 and hence the bail 34 and the trip pawl 56 have a time equal to the remaining two-ninths of a revolution of the filter shaft 36 to be restored. It has been found in operation that the timing is such that filter pawl 56 is always back into engagement with the lobe of the spring clutch in time to guarantee a single one-third of a revolution.

Continuing with the operation of the filter shaft 36, it can be appreciated that as soon as the filter pawl 56 drops into the path of one of the lobes of the primary 58, that the motion of the primary will be interrupted thereby unwinding the spring 66. If it were not for the complementary pawl 68, however, the spring would cyclically grab and release to provide a chattering action. The complementary pawl 68 is pivotally supported and spring biased into engaging position.

With this description it can be appreciated that a key stroke or a cycle is determined by a third of the revolution of the filter shaft 36. To reiterate, the rocking of the key lever 16 acts on the interposer to trip a spring clutch to cause a one-third revolution of the filter shaft 36, which in turn drives the interposer to the left thereby rocking predetermined selecting bails 44 to move the corresponding selecting links 48. The selecting links 48, during the one-third revolution of the filter shaft, select the character on the print head 8 which is to be printed on the sheet carried by the paper feed unit 6.

It follows that two operations which are distinct one from the other are necessary: (1) it is necessary to select the character and (2) it is necessary to print the selected character.

Selecting mechanism

As shown in Fig. 3, there are seven selecting links 48 which can be moved in response to the rocking of the selector bails 44. One of the links 48-1 is conditioned for operation for each key lever, and its function is to trigger a selecting clutch, while the other six links 48-2; 48-4; 48-6; 48-8; 48-10; 48-12 are used to condition dog clutches which in turn, determine the result which is produced by the selecting clutch under control of the link 48-1.

Reference is now made to Fig. 4B, wherein a selector belt 72 is shown continuously driven under control of a motor (not shown) to rotate a primary selector shaft 65 driving shaft 74 in a counterclockwise direction. The primary selector shaft is connected to a secondary selector shaft through a selecting clutch 76. Actually, the link 48-1 rocks the cycle bell crank 78 which is pivotally supported about a pin 80 carried by the frame. As the nose 82 of bell crank 78 is lifted out of engagement with the selecting clutch 76, the latter is actuated to drive the secondary selecting shaft 84 shown in Fig. 4A. The selecting clutch 76 is a conventional spring clutch of a type well known in the art. That is, as soon as the finger 82 is lifted out of engagement with the lobe 83, a spring

within the spring clutch will grip the primary selecting shaft 74 until the finger 82 again engages the lobe 83 to release the spring clutch. Selecting clutch 76 is a one revolution clutch, therefore only one lobe 83 is provided. The secondary shaft 84 carries a number of dog clutches which are triggered by the selecting links 48, and the dog clutches are conditioned for operation before the selecting clutch 76 is released to make a revolution.

In this respect, dog clutches 86-2, 86-4, 86-6, 86-8, 86-10 and 86-12, respectively, are provided to be operable in response to the movement of a corresponding selecting link 48. Since the operation of all the dog clutches are identical only one will be described.

Referring to Fig. 4A, each dog clutch 86 comprises a cam 88, an engaging dog 90 and a spring 92 tending to bias the dog 90 into engagement with a slot or key way 94 which runs along the secondary selecting shaft 84. The dog 90 is pivotally supported on a pin 96 carried by the cam 88 for rocking movement into and out of engagement with the key way of the secondary selecting shaft. In the disengaged position, as shown in Fig. 4A, a nose of the unlatching pawl 98 is hooked behind the tail of the dog 90 to rock the latter clockwise about its pivot pin 96 thereby disengaging the dog from the key way. If the unlatching pawl 98 is rocked clockwise about its pivot fulcrum 100, then the dog 90 is released, and under control of the spring 92, is pulled into engagement with the slot 94 of the secondary selector shaft 84 whereby as the latter is driven through a revolution, the cam 88 is also driven through one revolution.

In order to unlatch the dogs 90 from engagement with the slot 94 after the revolution is completed, the unlatching pawls 98 are spring biased into engagement with the tails of their corresponding dogs 90. Therefore, as soon as an interposer 22 is disengaged from the filter shaft 36, the unlatching pawl 98 snaps back into the position shown in Fig. 4A. The sequence of operation, therefore, is that unlatching pawl 98 is first rocked clockwise about the fulcrum 100; the tail of the dog 90 passes counterclockwise under the unlatching pawl 98 and drops into engagement with the slot 94 whereupon, as the cam 88 is driven through a revolution by the secondary selector shaft 84, the unlatching pawl 98 will be back in the position shown in Fig. 4A to grab the tail of the dog 90 and unlatch it by disengaging it from slot 94. Since the dog clutches should be engaged before the secondary shaft 84 starts to rotate, link 48-1 is connected to bell crank 78 via a link adjustment that permits the selected dog clutches to be tripped before nose 82 is released from lobe 83.

It has been mentioned that a spring 92 is used to drive the dog into engagement with the slot 94 in the secondary selector shaft. It can be appreciated therefore, that unless the cam 88 is blocked from moving, the combined action of spring 92 and unlatching pawl 98 will act to rotate the cam 88 clockwise and then dog 90 would not be in position to engage the slot of the secondary selector shaft at the next cycle of operation. Accordingly, a complementary latching pawl 102 is provided for each of the dog clutches to prevent rotation of the cam 88 while the dog 90 is unlatched. That is, the cam 88 is provided with a lug 104 and the interengagement of the lug 104 and latching pawl 102 will prevent clockwise rotation (as view in Fig. 4A), but will permit counterclockwise rotation of cam 88. Hence, toward the end of a complete cycle of rotation of cam 88, the lug 104 will act on the nose of the latching pawl 102 to raise it momentarily against the bias of a spring (not shown). Then as lug 104 passes under latching pawl 102, the latter will snap back to Fig. 4A position. It is this interaction of parts which blocks the clockwise rotation of the cam thereby keeping the dog disengaged from the secondary selector shaft until the unlatching pawl 98 is operated by its link 48.

To review the sequence then, there are six dog clutches

and one cycle clutch. At each operation of the key lever some combination of the dog clutches are engaged under the control of their respective interposers and links 48. After the dog clutches have been engaged, then the primary selector shaft drives the selecting clutch 76 through one cycle of operation thereby driving the secondary selector shaft and the engaged cams through one cycle of rotation. This latter action is designed to produce a selecting cycle which will now be described.

A cam follower arm 106, which is pivotally supported about either the upper pivot 108 or the lower pivot 110 (depending on its location), is provided for each cam 88, respectively. The rocking of a cam follower arm in response to the rotation of its corresponding cam causes a respective wire pulley 112 (carried by cam follower arm 106) to be raised or lowered (depending on its location) thereby rocking the cam follower arm clockwise or counterclockwise about its pivot 108 or 110 respectively. More specifically, the cam follower arm is provided with a cam follower 107 which is supported for rotation about a pivot 109 and the cam follower rides on one of the cams 88 driven by the secondary selector shaft. This rocking of the cam follower arms extends or contracts the effective length of a selecting wire 114, Fig. 4C, which has a path around the wire pulleys 112.

With reference to Figs. 4C and 4D of the drawings, the carrier 10 is illustrated schematically as being movable across a printing page between the left and right-hand margins. A carrier loop wire 116 is illustrated as 30 passing around pulleys 118 and 120 to be attached at one end 122 to the carrier 10 and at the other end 124 to a pulley 126 to which there is attached the printing head 8. In this arrangement, pulley 118 is fixed but free to rotate while pulley 120 is simultaneously rotatable and movable toward and away from pulley 118. If the pulleys 118 and 120 remain in the positions illustrated in Fig. 4C, the carrier 10 can be moved between the left and right-hand margins of the page, without any movement of the pulley 120. If, while the carrier is stationary, a movement is superimposed on the pulley 120, then the length of the carrier loop 116 will be either increased or decreased, and this change in length in the carrier loop 116 rotates the pulley 126 and thereby rotates the printing head 8 as later described. The pulley 126 is spring biased in a counterclockwise direction whereupon for each movement of the pulley 120 away from pulley 118, the spring will rotate pulley 126 counterclockwise; while movement of pulley 120 toward pulley 118 will rotate pulley 126 clockwise in opposition to the spring.

In this arrangement, it can be appreciated that the change in length of the selecting wire controls the rotation of pulley 126, and as later described, the position of the type head 8. With this analogy, it can be appreciated that any change in length of the selecting wire 114 as controlled by the movement of the wire pulleys 112 can be used to vary the position of a printing head. In this respect it should be mentioned that in a half of a spherical type element (as described in copending U.S. application, Serial No. 547,481, filed November 17, 1955), there are eleven rows of lower case characters; and in the other half there are corresponding eleven rows of upper case characters. The center row of each half sphere is designated as a home position and then the sphere is conditioned for rotation a maximum of 5 columns in either direction from home positions. When at rest, the lower case home position is in print position. More specifically, depending upon the movement of the wire pulleys 112, the type head can be rotated (in lower case) counterclockwise from home position one to five columns; or clockwise one to five columns. Then for upper case the type head is rotated first through 180° to position the upper case home position in print position before the selective column movement is superimposed.

As mentioned in copending application, Serial No. 547,481, the single element type head is both rotated and tilted. More specifically, there are four rows of characters and 22 columns of characters on the type head and normally the upper row and center column of the lower case characters is the designated home position held in print position. The rotation of the tilt pulley as mentioned in the copending application (Serial No. 547,481) causes the tilting of the head so that another row is positioned in printing position. In this respect (Fig. 4D), a pulley 132 is schematically connected to a tilting carrier loop 134 which is connected at one end 136 to the carrier and the other end 138 to the pulley 132. Once again the carrier is movable between a left-hand and right-hand margin without any turning of the pulley 132; but by superimposing a movement on tilt wire selector 140, the movable pulley 142 can be displaced with respect to a fixed pulley 144 thereby producing a rotation of the pulley 132 and a corresponding titling of the type head as disclosed in the copending application (Serial No. 547,481). The tilt wire selector 140 is movable under control of a pair of wire pulleys 146 and 148 which are operable in the same manner as the wire pulleys 112 except that these two are arranged to tilt the head one, two or in combination three rows of the type head away from home position thereby positioning any one of the rows at print position. The actual arrangement of the selecting pulleys is shown by the corresponding prime numbers in Fig. 4E.

With reference to the description of the selector mechanism, it will be appreciated that there are four of the wire pulleys 112 used for the turn selecting and the other two pulleys 146 and 148 make up the total of six selecting wire pulleys that are available for operation of the type head. In addition, there is a shift wire pulley which will be later described. It will be further understood that these wire pulleys are under control of the six selector links 48 so that with some combination of the available five clockwise or counterclockwise turn columns and 3 tilt units, any one of 44 characters can be presented to print position for the lower case; and by using the shift pulley, any combination of five rotational or three tilt units in upper case can be presented to printing position. The units of movement for each character are shown in the code chart of Fig. 4E.

Printing mechanism

The secondary selector shaft 84 has already been described as being rotatable in 360° cycles. This cyclic rotation of the secondary shaft is utilized to control the printing operation by mounting a pinion 150 (Fig. 4A) on the secondary shaft. The pinion 150 is connected via cog belt 152 to a carrier pinion 154 (equal in diameter to that of pinion 150) which in turn is pinned to a shaft 156, an extension of the square shaft 14 which is the forward guide for the carrier 10. With this construction, there will be a rotation of the square shaft 14, for every rotation of the secondary shaft 84. The rotation of square shaft 14 controls printing.

More specifically, the head 8 (Figs. 2 and 11) is supported on a rocker 158 which in turn is pivotally supported on a hollow bushing 160, Fig. 10, and carried by the carrier 10. With this arrangement, printing is effected when the rocker 158 is rocked clockwise about the bushing 160 thereby causing the type head 8 to engage a sheet held by the paper feed unit 6, Fig. 1. In order to effect the movement of the rocker required for a print stroke, the square shaft 14, as shown in Fig. 11 rotates a print cam 162 which is shown as having a single lobe, and cam 162 is shown engageable with a printing cam follower 164 which is a part of a link 166 which is supported for pivotal movement about a pivot 168, in turn supported on the carrier frame. The link 166 is also connected to the rocker 158 at pivot pin 170, Fig. 10. The link 166 is provided with elongated slot 172 which

permits transverse movement of the link 166 relative to the fixed pivot 168. With this construction, it is apparent that as the cam 162 makes a revolution its lobe will rock the follower 164 counterclockwise about the fixed pivot 168 thereby raising the rocker 158 to move the printing element 8 into printing engagement with the paper feed unit 6. Print cam 162 is slidable along shaft 14, and rotatable with it. In order to limit the depth of penetration of the character being printed, an anvil 163 is mounted on carrier 10 to be engageable with and stop the motion of rocker 158.

It should be observed that with this construction, a change can be made in the pressure or printing force of a type head print stroke by moving the pivot pin 168 forwardly or rearwardly in the slot 172.

Ribbon feed

The typewriter is provided with a ribbon feed mechanism to prevent a character from printing in exactly the same spot of inking ribbon as the other characters. The ribbon feed (Fig. 13) is accomplished through the provision of a ribbon feed cam 174 on the shaft 14, Fig. 11. The ribbon feed cam is slidable axially of square shaft 14, and rotatable with it. In this unique ribbon feeding mechanism a pair of spools 176 and 178 are rotatably supported on carrier 10. The ribbon is fed first on to one spool, and then on to the other in response to rotation of the ribbon feed cam 174. The ribbon feed cam 174 is also used to control the lift position of the ribbon; i.e. hold it out of the operator's line of sight and then lift it into a position between the printing character and the paper feed unit during a print stroke.

More specifically, the ribbon feed cam 174, in making one revolution in response to the revolution to the square shaft 14, performs the following functions:

First it permits the ribbon vibrator 180 which is pivotally supported for rocking movement about a pivot pin 182 mounted on the carrier 10 to be lifted by spring 179. The degree of lift of the ribbon vibrator 180 is controlled by the manual color control stop 184 which is rocked about a pivot point carried by the carrier 10. That is, one notch 183 at a time of the color control stop can be moved under the tail 185 of the ribbon vibrator 180 thereby determining the degree its opposite end 181 will be lifted.

The second function is to feed the ribbon and this is accomplished by the ribbon feed linkage 186 which is pivotally supported about pivots 188, 188a carried by the carrier 10. Rotation of cam 174 acts on cam follower 189 to rock pivot 188 and simultaneously put tension on spring 179 for ribbon lift. The ribbon feeding is accomplished by the upper end of the finger 187 which moves with pivot 188 and oscillates plate 190 to operate a pawl mechanism of a conventional type to rotate one ratchet wheel or the other at a time thereby advancing the inking ribbon past the printing position.

Escapement

In the operation of a mechanism of this sort, it is necessary to escape the carrier every print stroke and also to escape the carrier for inter-word space. To accomplish this objective, one mechanism is provided that will operate in conjunction with the secondary selector shaft 84 for normal escapement, and a second mechanism is provided that will work irrespective of whether or not the secondary shaft 84 is rotated thereby providing inter-word spaces.

In this respect, the carrier 10 is provided with an escape wire loop (Fig. 8) which is attached to the carrier and also has a portion wound around an escapement pulley 196 and attached thereto. The escapement pulley 196 is so chosen in size that less than a full revolution will cause the movement of the carrier completely across the page to be printed. In a preferred embodiment, the escapement wire loop 194 comprises the wire 198 and the

wire 199 each of which has one end secured to the carrier 10 and the opposite end secured to the escapement pulley 196. In this manner the escapement wire loop 194 is taut and also acts in response to the rotation of the escapement pulley 196 to move the carrier along its guides.

The escapement pulley 196 is supported on one end of shaft 200 which in turn is rotatably carried by a plate 202, and a circular escapement rack or ratchet wheel 204 is supported by the opposite end of shaft 200. The escapement rack 204 is spring biased by the coil spring 206 which forms a spring motor so wound that there is a bias for the escapement pulley 196 to turn clockwise thereby urging the carrier 10 to the right as viewed in Fig. 8.

In order to control the rate of escapement, a conventional pawl mechanism 208 is supported on a pawl carrier 210 which is attached to the base of the machine. When the pawl is released from a tooth on wheel 204, then in consequence of the bias on the wheel 204, and a slotted bearing in the pawl 208, the latter jumps over one tooth and into engagement with the next one thereby permitting the wheel to escape one tooth. This is a conventional mechanism and it is felt that it is not necessary to describe it in any further detail. The pawl 208 is released under control of the bell crank 212 which is pivotally supported about a pin 214 for movement in response to actuation of escapement link 216.

The escapement link 216, in turn, is mounted on an escapement follower 218 which is pivotally supported at 220 on a base plate. The escapement follower arm 218 carries a roller 222 which rides on a cam 224 which is secured to the secondary selector shaft 84 whereupon with each revolution of latter shaft, cam 224 is rotated thereby rocking the escapement follower 218 to rock the bell crank 212 and produce an escapement cycle by skipping the pawl 208 over a rack tooth and letting the carrier advance one space.

Space bar mechanism

For interword spacing, escapement is necessary without the rotation of the secondary selector shaft 84, and this is accomplished by the space bar mechanism. More specifically, space bar button 226 is carried by a space bar lever 228 which is fulcrumed, as are all the other key levers, about the pin 20 whereupon the depression of the space bar button causes rocking of the lever 228 to act upon the interposer 230 in the manner heretofore described to rock the latter clockwise about its pivot point thereby tripping the bail 34 to cause a revolution of the filter shaft 36 which as heretofore mentioned, will drive the interposer to the left as viewed in Fig. 8 thereby rocking the bell crank lever 234 counterclockwise about its pivot pin 236, thereby pushing forward on the escapement link 238 which in turn is secured to an end of the escapement follower 218 to rock the same about its pivot 220 to produce an escapement operation as has been already described.

Backspace mechanism

In addition to the mechanism shown in Fig. 8, the backspace mechanism as shown in Fig. 7 is also provided. More specifically, the escapement rack 204 is shown operable in conjunction with a backspace pawl 240 which is of conventional form. The backspace pawl 240 is pivotally connected to a backspace arm 242 which in turn is pivotally connected to a bracket 244 and spring biased by the spring 246 so that the backspace pawl 240 is urged into engagement with the escapement rack. A link 248 connects the backspace pawl 240 to a bell crank 250 which in turn is pivotally supported on a post 252 and a link 254 connects the bell crank 250 via a second bell crank 256 and another link 258 to a backspace rocker 260 which is pivotally supported on a pin 262 carried by the typewriter frame. The backspace rocker 260 is pivotally

connected to a link 264 which in turn is movable by a bell crank 266 which is driven by the interposer 268 acting under control of the filter shaft 36 as heretofore described. The backspace interposer in turn is controlled by a depression of a backspace key lever 270.

Shift mechanism

In dealing with a shift mechanism it must be recognized that the operator may wish to leave the typewriter in either upper or lower case while many characters are printed. That is, depending on the position of the shift key, the type head is conditioned for upper or lower case printing. In this respect—as in conventional typewriters—a pair of shift levers 272 and 274 are shown, in Figs. 2B, 2C and 2D, mounted about the fulcrum point 20 with the lever 274 having the usual locking mechanism 276 whereupon the shift lever can be locked in its depressed position. It should be understood that by depressing the lever 274 a little bit further, the lock 276 is unlatched to release the key lever when the operator's finger is removed.

In either event, depression of the key lever 272 (or key lever 274 acting through a bail 278 causing the key lever 272 to be rocked about its pivot 20) causes the interposer 280 to be rocked clockwise about its pivot point 26 thereby effecting an operation of the filter shaft 36 as has heretofore been described. This causes the interposer 280 to be driven to the left as viewed in Fig. 2B to rock the bell crank 282 and push on link 284 in the direction of the arrow as viewed in Fig. 2B. The uniqueness of this mechanism is such that when the interposer 280 is driven to the left as viewed in Fig. 2B, it is knocked off the shift lever finger 286 as with the other interposers, but in this case, the interposer 280 cannot be restored to its rest position while the key lever 272 is held depressed. Actually, the finger 286 is designed so that when the interposer is driven to the left as viewed in Fig. 2B, the ear 288 gets behind the finger 286 and so long as the key lever is held down, the bell crank 282 will be held in its rocked position, thereby holding the link 284 forward to its operative position.

In this respect, the forward movement of the link 284 rocks a finger 287 which carries an integral primary unlatching pawl 290, Fig. 2C, which is pivotally supported about a pivot 292, to get the nose 294 of the pawl 290 out of engagement with the lobe on a primary cam 296 thereby releasing the latter which is under control of a spring clutch, causing the primary to turn clockwise so that the spring grips the hub of a continuously rotating gear 298 which is driven by a pinion 300 carried by the primary selector shaft 74. The spring clutch gripping the hub of the gear 298 causes rotation to drive a secondary cam 302 which in turn is pinned to a shaft 304 causing rotation of that shaft 304, and consequently of a shift gear 306 which is shown in Fig. 4B. It might be noted at this point that there is a gear reduction of 2 to 1 between the pinion 300 and the continuously rotating gear 298. Therefore, the shaft 304 rotates at only half the speed of the primary selector shaft 74.

It will be noted that when the link 284 is pushed forward under control of the interposer 280, that the lobe of the primary cam 296 will be engaged by the nose 295 of the finger 287 after cam 296 has made a half revolution. So too, an overthrow pawl 312 is positioned to engage a lug on the secondary cam 302 holding the spring of the spring clutch disengaged. It is apparent then that with each operation of the link 284 only a half revolution is imparted to the shaft 304 and this half revolution, in driving the cam 308, Fig. 4B, through the interconnection of the pinion 306 and a cam gear 314, can drive the cam 308 only a half revolution. And since this cam is provided with only one lobe displaced 180° from rest position it can be recognized that a half revolution of cam 308 will cause the maximum change. The cam 308 is actually connected to a second cam (not shown)

with the two rotating as a unit about the secondary selector shaft 84 as a bushing. The high dwell of these cams is used to rotate the print head 8 180° by spreading the pulleys 309, 310 (Fig. 4C) and hold it in upper case position as long as the key lever 272 is held depressed.

Upon release of the key lever 272, the spring 318 restores the interposer 280 to its normal position shown in Fig. 2B whereupon the link 284 is restored to its Fig. 2B position thereby disengaging the finger 287 so that its nose 295 releases primary cam 296 for another half revolution until its lobe engages the nose 294 of the primary unlatching pawl 290. During this movement, through mechanism already described, the shaft 304 will make another half revolution to drive the cams 308 a half revolution back to their rest position whereupon the print head will be returned to its lower case home position.

Carriage return mechanism

The escapement pulley 196 (Fig. 6), the same as that shown in Fig. 8, and the escapement rack 204 are shown operable under the control of escapement pawl 208. The rack 204 is provided with a hub 320 about which is wrapped a pull tape 322 which in turn is carried around pulleys to a clutch operated driving member 324.

The carriage return key lever 326 is pivotally supported about the fulcrum rod 20 and it carries the usual trip finger 328 which acts on the interposer 330 to rock the same about its pivot 26 under control of the filter shaft 36 which in turn will rock the bell crank 332 to push on link 334 to rock the crank arm 336 clockwise about a pivot 338 to pull on a carriage return operating plate 340. This movement will drop an arm 342 of the carriage return plate behind a stop 344 and hold it there until it has been unlatched. The forward movement of the carriage return operating plate 340 acts on a carriage return lever 346 to rock a crank 348 counterclockwise about its pivot 350 thereby pushing the capstan 352 axially into engagement with a positive ratchet clutch 354. The interengagement of the capstan 352 with the clutch 354, which in turn is driven by the pulley 52, under control of the belt 50, Fig. 3A, causes the capstan 352 to wind up the pull tape 322, which has heretofore been mentioned as wrapped around the drum 320, to restore the escapement rack 204 towards a normal position which would correspond to the left-hand margin of the carrier 10. As the escapement rack 204 is rotated toward the left-hand margin position a margin stop 356 engages a pin 358 on the rack 204 which rocks the margin stop 356, and acting through the bell crank 360 pulls on a link 362 to unlatch the carriage return latch 342 removing it from the stop 344 thereby restoring the carriage return operating plate to its normal position shown in Fig. 6 and releasing the clutch 354 to separate the capstan 352 from the pulley 52.

As a matter of incidental interest, it should be mentioned that when stop 342 is put behind the stop 344, the rocking of the bell crank 363 pulls on link 362 so that the pull in the link 362 rocks the bell crank 360. It also acts on the tail of pawl 208 to disengage it from the rack 204 thereby preventing a drag of the pawl on the rack during the carriage return operation. Furthermore, the pull on link 362 acting through bell crank 360 will tilt the margin lever 356 counterclockwise from its position shown in Fig. 6 so it reaches out to engage the pin 358 as the latter is moved towards it. Then it is the movement of the margin stop 356 back to its position shown in Fig. 6 which unlatches the carriage return latch 342 to disengage the capstan 352 from the pulley 52.

Indexing mechanism

As in conventional mechanisms, this new and improved typewriter is provided with a platen 364, Fig. 5A, which is a part of the paper feed unit 6. The platen is rotatably supported in the end plates of the paper feed unit 6. Furthermore, the platen is provided with a ratchet wheel 368

of conventional design. In order to advance the platen for paper indexing, the ratchet wheel 368 is driven by the pawl 374. More specifically, the pawl 374 is pivotally supported on a carrier arm 376 which in turn is supported in the end frame at the pivot point 378. The carrier arm 376, being pivotal in the end frame, will permit the pawl 374 to engage the teeth of the ratchet wheel 368 when a link 380 is moved vertically downward thereby rotating the ratchet wheel to advance the platen. Obviously, conventional adjustment means can be provided to facilitate single, double, or triple line spacing in a manner well known in the art. The link 380 is connected to an auxiliary link 382 via the pin 384 and spring 386. Furthermore, the auxiliary link 382 is provided with the elongated slot 388 so that there can be relative movement between the auxiliary link 382 and the primary link 380. More specifically, when the pawl 374 hits a stop (not shown), preventing the link 380 from travelling further downwardly even though the auxiliary link 382 travels further, the spring 386 will absorb the pull from the auxiliary link 382 and the slot 388 will simply slide over the pin 384.

In order to move the link 380 downwardly to effect the indexing, a crank arm 390 is pinned to a shaft 392 to which there is also attached a bell crank 394 which in turn is pivotally connected to a link 396 that is attached to the indexing cam follower 398. The latter is pivotally supported about a bearing pin 400, Fig. 5B, so that rocking of the indexing cam follower counterclockwise about the pivot pin will pull on link 396 and rock the crank arm 390 clockwise thereby pulling on auxiliary link 382 and link 380 to operate the pawl 384 for an indexing motion.

In order to rock the indexing cam follower 398 an eccentric 402, which is carried by a cam 404, is supported for rotating about the shaft 304 within a slotted opening 408 provided in the indexing cam follower 398. The shaft 304 also rotatably supports a ratchet wheel 410 which in turn is connected to the gear 298 (Fig. 2C) which is continuously driven by the pinion 300 previously described with respect to the shift mechanism. When this structure is continuously rotating, ratchet wheel 410 can be engaged by a dog 412 which is pivotally supported at 414 on the cam 404. It is obvious that when the tooth of the dog engages the ratchet wheel 410 the cam 404 will rotate and carry with it the eccentric 402 thereby oscillating the indexing cam follower 398. The dog 412 is controlled by an unlatching pawl 416 which in turn is pinned to and rotatable with shaft 418 that is supported in the carriage frame. It is apparent that when the unlatching pawl 416 is rotated clockwise, it will be removed from engagement with the tail of the dog 412 whereupon a spring 420 will pull the dog into engagement with the ratchet wheel to drive the cam 404 and this driving will continue until the unlatching pawl 416 drops back in the position shown in Fig. 5A. The unlatching pawl drops back a few milliseconds after it has released dog 412, thereby guaranteeing that the dog will be unlatched after it has made one revolution and has returned substantially to the position as shown in Fig. 5A. In this respect, an overthrow pawl 422 is provided to engage a shoulder 424 on the cam 404 to prevent back travel of the cam and thereby insure the fact that the dog 412 will be kept out of the ratchet wheel 410.

The unlatching pawl is controlled by a link 426 which can move to the right as viewed in Fig. 5A to rock the unlatching pawl 416 clockwise with the shaft 418, to disengage it from the tail of the dog 412. The link 426 in turn is controlled by a bell crank 428 that includes a pivotal finger 430 which is positioned for engagement by the interposer 432 in the same manner as that described for the other interposers: namely by depression of the key lever 434 and the rotation of the filter shaft 36.

With reference again to the carriage return mechanism, it is obvious that an interconnection must exist between

the indexing mechanism and the carriage return mechanism in order to advance the platen as the carrier is returned to its left-hand margin position. Yet it is desirable to permit indexing, separate from the carriage return mechanism, and this interrelation is accomplished in the following manner. With reference to Fig. 6, the crank arm 336 is provided with a bent over ear 436 which is positioned for engagement with a bell crank 438 which is pinned to the shaft 418. It follows therefore, that rotation of the crank arm 336 through the operation of the bent over ear 436 will rock a bell crank 438 and shaft 418 to rotate the unlatching pawl 416 and thereby cause an indexing operation. On the other hand, if the index mechanism is operated separately from the carriage return mechanism, the shaft 418 will be rotated with the rocking of the unlatching pawl 416, but since there is not a positive interconnection between the bent over ear 436 and the bell crank 438, then the latter can rotate free from the bent over ear 436 and accordingly, the carriage return mechanism will not be operated.

Tabulation mechanism

As described with respect to the escapement mechanism in Fig. 8, an escapement pulley 196 is supported on shaft 200 which in turn is attached to an escapement rack 204. The rack 204 is provided with a plurality of apertures 440 (Fig. 9) which accommodate pins 442. The pins 442, as shown in the partial section view, are supported in the C type frame which is made up of the combination of the rack 204 and a baseplate 444. Each of these members have aligned holes or apertures 440 with one for each column space of the platen. If these pins are moved up, then the pin is in a position to act as a margin stop; while if the pin is slid down, it is then in position to act as a tap stop, while if the pin is in the center, it is neutral and is neither carriage return nor tab. Friction material such as rubber or the like is carried between the base member 444 and the rack 204 to hold the pins from sliding one way or the other. With this arrangement of parts, depending upon which column pin 442 has been moved to a tap stop position, the rotation of the rack 204 during a tabulation run will be stopped in the following manner. A tab stop lever 446 and a tab check lever 448 are separately pivotally supported at 450 for movement into and out of engagement with the pins 442 (Figs. 9A and 9B). The pivot 450 is supported on a bent over ear 452 which in turn is attached to the carriage base plate. The tab stop 446 and tab check lever 448 are moved as a unit into engaging position with the pins 442 by means of the link 454 and they are held in this position by a latch 456 where they will remain until unlatched by the operation of the pin 442 hitting the tab stop 446. More specifically, when the pin 442 rotates clockwise during a tabulation run, the pin will hit the tab stop 446, Fig. 9B, and pull it to the right along the path of movement of the pin 442 to unlatch the latch 456 whereupon the escapement pawl 208 will be returned to the rack 204 as will be hereinafter described. The tab stop 446 and tab check 448 are released from the engaging position with the pin 442 and brought back to their normal position.

It is obvious that there has to be an interconnection between the pawl 208 and the tab mechanism so that the rack 204 will be free to rotate during a tabulation run. To accomplish this end, the link 454 is connected to a bell crank 458 which is pivotally supported at 460. Bell crank 458 carries a pin 462 which is in slotted engagement with a second bell crank 464, which in turn is pivotally supported by pin 466. The bell crank 464 is engageable with the tail of the pawl 208 whereupon since the pin 462 is on the same side of the bearing 466 as is the arm 464 it is apparent that any movement of the pin 462 in the direction of the arrow of Fig. 9 (and Fig. 9A) will cause the pawl 208 to be rocked clockwise about its supporting pin and out of engagement with the rack teeth.

In this manner, with the pawl 208 being raised out of engagement with the teeth of the rack 204, and being interconnected with the tab stop 446 and the tab check 448, what happens is that as the rack rotates and the pin 442 is stopped by the tab stop 446, the rack will bounce back. That is, after the pin hits the tab stop 446, the rack will rebound enough to release the friction on the tab stop which then can rotate counterclockwise as viewed in Fig. 9A under the influence of spring 468 which action restores the pin 462 to its position shown in Fig. 9B and thereby releases the pawl 208 to drop back into the rack tooth. It is also to be noted that the tab stop 446 is not completely removed from the path of the pin 442 before the pawl 208 has been dropped back into the rack 204. Accordingly, there is no possibility of the escapement rack 204 being free to run away.

In essence then, the operation of the tabulation mechanism is similar to the other operations heretofore described. More specifically, the depression of a key lever 470 depresses the interposer 472 to trigger the bail 34 to cause the rotation of the filter shaft 36. This rocks the bell crank 474 to exert a pull on the link 476 which in turn rocks the bell crank 458 and pulls on pin 462 to unlatch the pawl and to set the tabulation mechanism to be engageable with one of the pins 442.

Timing

In order to explain the operation of this mechanism, a description will be given of the complete operation of two print strokes. That is, starting from the initial depression of the key lever right through the mechanism of the typewriter until the character prints and the carrier escapes, thereby completing one print cycle.

In the curve of Fig. 14, the timing is laid out in milliseconds and in order to appreciate the true value of this mechanism, it should be understood that in very high speed typing a character rate is in the order of 20 characters per second in conventional machines. Twenty characters per second is equal to one print stroke every 50 milliseconds, and accordingly, if this improved machine will function satisfactorily at a rate so that a second key lever can be depressed, and operate satisfactorily in less than fifty milliseconds, then it will surpass the operation of the conventional machine.

Following through with this line of thought, reference is now made to Fig. 14, wherein the pulley 52 of the filter shaft is indicated as rotating at 400 r.p.m. while the primary selector shaft 74 is illustrated as running at 1200 r.p.m. Then under these conditions, a key lever 16 is shown depressed at the reference mark indicating zero milliseconds, with the complete depression taking place within 15 milliseconds. The key lever 16 depresses the bail 34 to initiate a filter clutch operation in the same time period, and the latter at 10 milliseconds has initiated a one-third revolution of the filter shaft 36. The filter shaft 36 when it starts its operation, moves the interposer 22 to rock the selector bails 44 and the interposer will have travelled its complete actuating distance within 15 milliseconds. The motion of the interposer in turn triggers the clutch 83 to drive the secondary selector shaft 84 through one revolution.

It can also be seen that during the same intervals of motion, the links 48 have triggered the selector cams 88. It is to be understood that the interposer in the first 10 milliseconds of its operation triggers the one revolution clutch 76 to drive the secondary selector shaft 84 but during the same ten milliseconds while the secondary selector shaft 84 was being triggered for operation, the interposer had already dropped the clutch dogs 90 for the cams 88 into engaging position so that they are ready to move as soon as the secondary shaft 84 starts moving. The selector cams will move to their high dwell position within 20 milliseconds and remain at the high dwell for 10 milliseconds before returning to their rest position.

Simultaneously, since the secondary selector shaft 84

is being rotated, the ribbon lift vibrator will move concurrently with the selector cam and the ribbon feed pawl 186 will move concurrently with the selector cams before the print rocker 158 reaches printing position. By the time the rocker 158 is at printing position the selector cams will be at their high dwell, the ribbon lift will be in printing position and the ribbon feed will have taken place. At that instant or 48 milliseconds after the initiation of a print stroke, the print rocker 158 will effect the printing of the character on the paper. Just before actual print time of 48 milliseconds, the cam 224 will have rotated to trip the pawl 208 out of the rack 204 to start the carrier escapement. Since the rack will just barely start moving before the actual print time, there is no impairment to the operation of this mechanism and the actual carriage escapement will cease at the 85 millisecond mark. Actually then it takes 85 milliseconds for a complete type bar print stroke but the important thing is that a second type bar print stroke can be started long before the carrier escapement has come to rest. This is illustrated by the corresponding parts marked *a*; for example, by a second key lever marked 16a and its associated mechanism which will bear the symbol *a* corresponding to the part used for the first print stroke, as shown in Fig. 14. That is, a second print stroke can be initiated any time after 15 milliseconds from the initiation of the first print stroke. Specifically, reference is made to a second key lever 16a which is depressed starting 15 milliseconds later than the key lever 16 and accordingly, the bail 34 which normally would have restored to its rest position, is held down by the second key lever 16a and since the bail is held down at the point where the 1/3 revolution of the filter shaft should be interrupted, the latching pawl 56 will not be in position to engage one of the shoulders 58 on the cam and accordingly another third revolution of the filter shaft will take place which, consequently, will carry with it the interposer 22a held down by the second key and the motion of the interposer of the second key is indicated as starting at the 60 millisecond mark, and during the motion of that interposer, the secondary selector shaft 84 will be triggered for operation, but during that same ten milliseconds the dogs of the clutches 88 will have been positioned in the key way of the shaft 84 so that the selector cams will be ready for rotation, when the secondary selector shaft starts to rotate. Simultaneously as heretofore described the ribbon lift 180 will operate and the ribbon feed 186 will take place and the rocker 158 will be started towards print position about 14 milliseconds after the secondary selector shaft starts to rotate which is in accordance with the motion for the first print stroke, and by the time the actual print stroke takes place, the carrier 10 will have come to rest at the 85 millisecond mark as heretofore described so that at the moment of impact or the second print stroke the selector cams 88A will be at the high dwell, the ribbon lift 180 will be in position and the ribbon feed will have taken place.

It follows that with this description of parts that any print stroke that starts 15 milliseconds after a previous one will be carried through to completion without interference with the first print stroke. However, a third print stroke cannot be started within 65 milliseconds from the time of the first print stroke. If a third stroke is started ahead of time, there will be no clashing of any sort but rather two interposers will be positioned to be driven by the shaft 36 at the same time and accordingly the combination of fingers on the two interposers will determine what character is to be printed.

In actual test and operation it has been found that this mechanism will function satisfactorily at a character print rate of approximately 19 characters per second.

Mounting for spherical head

It has been mentioned that the details of the spherical head are described in copending application Serial No.

547,481. In essence (Fig. 10), the tilt pulley 132 and the rotation pulley 126 are mounted on shafts concentrically disposed within the tube 9 which shafts are described in copending application Serial No. 457,481. 5 The tube 9 merely positions the head on the carrier while the internal concentric shafts are free to rotate within the tube 9 and their rotation controls the tilting and turning of the head 8. The internal shafts are connected one to the tilt pulley 132 and one to the rotation pulley 126 so 10 that the rotation of these pulleys selectively turn and tilt the head 8. It has also been mentioned that there is a home position for the head 8 which is the upper row of characters in the central column of the lower case half of the printing head. This home position is maintained 15 by a pair of springs not shown in Fig. 10. More specifically, clocksprings 478, 480, Figs. 4D and 4C, are positioned respectively in engagement with the pulleys 132, 126. Then when the head is rotated or tilted away from home position there will be a resiliency tending to urge 20 the head back to its home position. The turn carrier loop 116 and the tilt carrier loop 134 pass through the pivot bushing 160, Fig. 10, and then are attached respectively to the rotation pulley 126 and the tilt pulley 132 as heretofore described. 25 The pivot bushing 160 is mounted in the carrier 10 in such a manner that the rocker 158 is supported for pivotal movement toward and away from a printing position. The pulleys 132 and 126 move with the rocker 158 and all pivot about the center of the pivot bushing 160. The 30 rocker, in turn, is moved in response to the pivoting of the link 166 through the rotation of the cam 162 as previously described. 35 With this construction, it is to be particularly noted that the center of the pivot bushing 160 is in alignment 40 with the periphery of the turn pulley 132 and the rotation pulley 126 so that the wires that are wrapped around these pulleys simply twist about their own axis as the head is moved into printing position, and through this action, it has been found that the turn carrier loop and the tilting carrier loop will operate satisfactorily without breaking through many thousands of operations.

Paper feed unit

The paper feed unit 6 (Fig. 12) comprises a base 482 45 and a pair of side plates 484, 486 which carry the platen 364, a paper deflector 488, and paper feed roll unit 490 in addition to the conventional paper bail 492 which is pivotally supported on arms 494 and 496 which in turn are supported on the side frames 484, 486 respectively.

50 The platen 364 is so supported that its shaft 498 fits in the bearing slots 500 in a conventional manner to be locked in place by the locking ears 502, 504 respectively.

The paper feed roller unit 490 is of conventional design in that it carries a base rod 506 which carries three pivot 55 arms 508, 510 and 512 which in turn support a pair of yokes 514 and 516 about at their center to provide for the pivoting of the yokes relative to a shaft 513 which interconnects the arms 508, 510 and 512. Each of the yokes carries a front and rear paper feed roller shaft 518, 60 520 respectively with the pivotal feed rollers mounted on each shaft. This construction is such that the rotation of the shaft 506 in a counterclockwise direction rocks the arms 508, 510 and 512 to lower the shaft 513 and thereby drop the yokes, consequently the paper feed rolls 65 are moved away from the platen 364 to relieve the paper feed rollers from driving engagement with the platen. In this latter respect, the spring 522 holds the shaft 513 and consequently the yokes 514 and 516 upward in engagement with the platen 364.

70 It should be mentioned that the deflector 488 is normally in position between the feed roller unit and platen 364. The deflector normally is secured to the yokes 514 and 516 in such a manner that the feed rollers extend through suitable apertures in the deflector for contact with the platen 364. When the shaft 506 is rocked counter-

clockwise as viewed in Fig. 12, the pressure of the feed rollers against the platen is removed. This rotation of the shaft 506 is accomplished by a crank arm 524 which is positioned to be rotated in response to the pivoting of a bell crank 526 which is pivotally supported on the end frame 486 at a point 527.

Provision is also made for releasing the detent pressure on the ratchet wheel 368 and is accomplished by means of rocking the arm 528 which is pivotally supported at 530 in the side frame and the arm 528 carries a detent 532 which normally is engageable with the ratchet wheel 368 but can be released therefrom by rocking the crank arm 528 clockwise thereby leaving the ratchet wheel 368 free to rotate. This is a conventional mechanism.

While there have been shown and described and pointed out the fundamental novel features of the invention as applied to a preferred embodiment, it will be understood that various omissions and substitutions and changes in the form may be made by those skilled in the art without departing from the spirit of the invention. It is the intention, therefore, to be limited only as indicated by the scope of the following claims.

What is claimed is:

1. A typewriter comprising a paper carrier, a printing head having a plurality of characters arranged thereon in the manner wherein only one character at a time may be located at printing position, means mounting said printing head to permit both character spacing movement across said paper carrier and rocking movement of said head into and out of printing engagement with said paper carrier, a plurality of key levers, a printing mechanism operable for rocking said head into printing engagement with said paper carrier, and control means for selecting and printing a character in response to manipulation of said key levers, said control means comprising a printing cam for operating said printing mechanism, a plurality of selecting cams having individual clutches, a selecting shaft for driving said printing cam and those selecting cams having engaged clutches, and means responsive to the rotation of said selecting cams for determining the print head character that is moved to printing position.

2. The structure of claim 1 wherein said selecting cam responsive means comprises a flexible strand system having a uniform path length while said key levers are at rest position, means manipulating said head to change the character in printing position in response to a change in path length of said strand system, and means for varying the path length of said strand system comprising a plurality of wire pulleys mounted for both peripheral engagement with said strand system and for pivotal movement radial to said strand system in response to rotation of said selecting cams.

3. A structure in accordance with claim 1 wherein said selecting cam clutches are operable under control of a plurality of bails which are individually mounted for rocking movement transversely of said key levers, and permutation means for rocking a predetermined combination of said bails in response to the manipulation of any of said key levers respectively.

4. A typewriter comprising a paper carrier, a printing head having a plurality of characters arranged thereon in such a manner that only one character at a time may be located in printing position, means mounting said head for rocking movement into printing engagement with said paper carrier, a plurality of key levers, and means responsive to the manipulation of said key levers for controlling the cyclic rate of print strokes of said print head comprising a printing cam for rocking said head into engagement with said paper carrier, a selecting shaft for driving said printing cam, clutch controlled means for connecting said selecting shaft to a power source for one cycle of operation, and means tripping said selecting shaft clutch whereby said selecting shaft is driven through one cycle of operation to cause a printing stroke, said last named means comprising a bail mounted transversely of

said key levers for rocking movement, link means interconnecting said bail and said selecting shaft clutch for operation of the latter in response to rocking of said bail a filter shaft, means connecting the same via a clutch to a power source to provide cyclic rotation of said filter shaft in response to manipulation of a key lever, and means interconnecting said filter shaft and said bail to provide for rocking of the latter as said filter shaft goes through a cycle of operation.

5. In a typewriter having a single printing element with characters arranged thereon in such a manner that one character at a time may be positioned in printing position a plurality of key levers, means interconnecting said key levers and printing element to select a character to be printed, and means for rocking said element to print a selected character, a mechanism in said interconnecting means for cyclically controlling the rate of print stroke comprising a filter shaft connected via a clutch to a power source to permit cyclic operation of said filter shaft in response to the triggering of said clutch, a plurality of interposers assigned individually one to each of said key levers, means mounting said interposers for rocking movement into engagement with said filter shaft in response to manipulation of said key levers, and means responsive to the rocking of said interposers for triggering said filter clutch to drive the same through one cycle of operation.

6. A typewriter comprising a single printing element having characters arranged thereon in such a manner that only one character at a time may be positioned in printing position, a plurality of key levers, means for rocking said element to print a selected character, and means interconnecting said key levers and printing element to select a character to be printed comprising a filter shaft connected via a clutch to a power source, a plurality of interposers assigned individually one to each of said key levers, means mounting said interposers for rocking movement into engagement with said filter shaft in response to manipulation of said key levers, means responsive to the rocking of said interposers for triggering said filter clutch to drive said filter shaft through one cycle of operation, a plurality of bails mounted transversely of said interposers, a selecting mechanism responsive to the rocking of said bails, and means responsive to the movement of said interposers resulting from the inter-action thereof with said filter shaft for rocking said bails to effect the selecting operation.

7. A claim in accordance with claim 5 wherein means are provided to be operable in response to the interengagement of said interposers with said filter shaft for selecting a character to be printed.

8. In a typewriter having a single printing element with characters arranged thereon in rows and columns in manner wherein only one character at a time may be located in printing position, a plurality of key levers means interconnecting said key levers and printing element to select the character to be printed, and means for rocking said element to print the selected character, a mechanism in said interconnecting means for cyclically controlling the rate of character selection comprising a filter shaft mounted transversely of all of said key levers a power source connected via a clutch to said filter shaft for driving the same through a single cycle of operation each time said clutch is triggered, a plurality of interposers assigned individually one to each of said key levers means mounting said interposers for rocking movement into and out of engagement with said filter shaft in response to manipulation of said key levers, said interposer mounting means further permitting displacement thereof in response to the cyclic rotation of said filter shaft, a plurality of bails mounted transversely of said key levers for rocking movement in response to displacement of said interposers, means operable in response to the rocking of said bails for selecting a printing element character to be printed, said interposers having combinations of fingers for operating said bails with one com

ination being assigned to each of said key levers, and means operable in response to the rocking of said interosers for triggering said clutch thereby driving said latter shaft through one cycle of operation to select a character to be printed.

9. In a typewriter having a single printing element with characters arranged thereon in rows and columns, wherein only one character at a time may be positioned in printing position, a plurality of key levers, means interconnecting said key levers and printing element to select character to be printed, and means for rocking said element to print the selected character, said selecting means including means for rotating said print head, and means for tilting said print head, said rotating and tilting means each comprising a flexible strand system having a uniform path length when a predetermined character is in printing position, means responsive to a change in path length of said strand system for tilting and rotating said head respectively, means for varying the path length of each of said flexible strand systems, and means operable under control of said key levers for operating said path length varying means.

10. The structure of claim 9 wherein each of said strand length varying means comprises a plurality of wire pulleys pivotally mounted in peripheral engagement with said strand system, a plurality of selecting cams connected via clutches for driving relation with a selecting shaft, said cams further being engageable with said wire pulley mounting means to pivot the latter and produce radial movement between said wire pulleys and said flexible strand system, and means operating said clutches in predetermined combinations in response to the manipulation of a key lever thereby varying the path length of each of said strand systems respectively.

11. In a typewriter having a single printing element with characters arranged thereon in rows and columns wherein only one character at a time may be located in printing position, a plurality of key levers, means interconnecting said key levers and printing element to select the character to be printed and means for rocking said element to print a selected character, a mechanism for

rotating and tilting said print head to present a selected character in printing position comprising a flexible strand system having a uniform path length when at rest position, pulley means secured to said head to provide for 5 rotating and tilting the same to position a selected character in printing position, said pulley means being connected in said flexible strand system in a manner whereby when the strand system is at its rest position a predetermined character is always in printing position, means 10 for varying the path length of said strand system thereby displacing said pulley means to position a different character at printing position, and means operable under control of said key levers for varying the path length of said strand system comprising a plurality of wire pulleys 15 pivotally mounted for peripheral engagement with said strand system, a selecting shaft having driving means, a plurality of selecting cams mounted for driving relation with said selecting shaft under control of selectively operable clutches, said selecting cams further being engageable with said wire pulley mounting means to pivot said wire pulleys and move them radially of the strand system thereby varying the path length of the latter in response to the operation of said selecting cams, a plurality of bails 20 mounted transversely of said key levers, linkage means interconnecting said bails with said selecting cam clutches to provide for the operation of the latter in response to the rocking of said bails, and permutation means for operating a specific combination of said bails in response to the manipulation of a key lever.
